UNITED STATES PATENT OFFICE

2,001,580

ELECTRIC FLASHER

Louis Ludwig, Brooklyn, N. Y.

Application May 24, 1933, Serial No. 672,551

4 Claims. (Cl. 200—115.5)

The invention relates to electric flashers or current interrupters and has for its main object to provide a device of very simple construction in which the various parts can be manufactured at low cost and assembled with a great saving of time and labor. Another object is to so construct the device that breakage and distortion of any of its parts are reduced to a minimum.

These and other objects and advantages will be readily understood from the following description and from the accompanying drawing, in which

Fig. 1 is a cross-sectional, side elevation of a flasher constructed in accordance with the invention;

Fig. 2 another side elevation with some of the parts removed;

Fig. 3 a top view of Fig. 1;

Fig. 4 a cross-sectional, bottom view, taken on line 4—4 in Fig. 1;

Fig. 5 another side elevation shown partly in cross-section; and

Fig. 6 a cross-sectional, side elevation of a slightly modified part of the flasher.

so that it will cut its own threads in the hole when inserted. Another angular contact member 26, which carries a contact point 27, is inserted in the lower end of the body member. When the body member is made in two parts, the parts are held together by the shell 14 and by a metal ring 28 which is snapped into a groove 29 moulded in the parts near their upper ends.

In the slightly modified body member, shown in Fig. 6, the parts are mounted as in the embodiment just described. The upper center-contact member and the thermostatic element are secured by a screw threaded in the hole 30, and the leg of the lower contact member is made to fit tightly in the slot 31. A hole 32 is provided in the side of the body member to facilitate the insertion of the screw in the hole 30.

From the foregoing it will be seen that the process employed in constructing this device makes it possible to assemble its parts with ease and at a high rate of speed, and that it assures the correct positioning and alignment of all the parts.

Having described my invention and its object, what I claim as new and wish to protect by Letters Patent is:

1. As an article of manufacture; an electric flasher consisting of an insulating body member containing an upper compartment, having openings in the bottom leading to the exterior, and a smaller lower compartment, having a supporting boss and also a slot leading to the lower outer end of the body member; a threaded metal shell, having downwardly extending lugs, secured in the upper compartment with the lugs projecting through the openings leading to the exterior of the body member; an upper center contact and a thermostatic element secured to the boss in the lower compartment; a lower center contact secured in the slot in bottom of the body member; and a threaded metal shell secured on the lower end of the body member and contacting with the lugs of the metal shell contained in the upper compartment.

2. As an article of manufacture; an electric flasher consisting of an insulating body member containing an upper compartment, having openings in the bottom leading to the exterior, and a smaller lower compartment, having a supporting boss and also a slot leading to the lower outer end of the body member; a threaded metal shell, having downwardly extending pierced lugs, secured in the upper compartment with the lugs projecting through the openings leading to the exterior of the body member; an upper center contact and a thermostatic element secured to

45

An insulating washer 20 is placed in the bottom of the shell 13. It is provided with a rectangular slot through which one leg of the angular center-contact member 21 passes. The leg is secured to a support 22, which is moulded on the body member, by means of a screw 23. The thermostatic element 24 is also held in place by means of this screw. The element is of the ordinary type on which a resistance wire is wound, and is provided with a contact point 25. The screw 23 is preferably of the so-called "self-tapping" type

the boss in the lower compartment; a lower center contact secured in the slot in the bottom of the body member; a threaded shell secured on the lower end of the body member; and said shell having upwardly extending tongues bent into the piercings in the lugs of the metal shell contained in the upper compartment.

3. As an article of manufacture; an electric 10 flasher consisting of a two-part insulating body member which, when assembled, contains an upper compartment having openings in the bottom leading to the exterior and a smaller lower compartment having a supporting boss and a slot leading to the lower outer end of the body member; the body member provided with a circumferential groove on the outside at its upper 15 end; a threaded metal shell, having downwardly extending lugs, secured in the upper compartment with the lugs projecting through the openings leading to the exterior of the body member; an insulating washer, having a centrally located rectangular slot, secured inside the metal shell; an upper center contact extending through the slot in said washer and secured together with a 20 thermostatic element to the boss in the lower compartment; a lower center contact secured in the slot in the bottom of the body member; a threaded metal shell secured on the lower end of the body member and contacting with the lugs 25 of the metal shell contained in the upper compartment; and a ring contained in the circum-

ferential groove for clamping the body parts together.

4. As an article of manufacture; an electric 5 flasher consisting of a two-part insulating body member which, when assembled, contains an upper compartment having openings in the bottom leading to the exterior and a smaller lower compartment having a supporting boss and a slot leading to the lower outer end of the body member; the body member provided with a circumferential groove on the outside at its upper 10 end; a threaded metal shell, having downwardly extending and pierced lugs, secured in the upper compartment with the lugs projecting through the openings leading to the exterior of the body 15 member; an insulating washer, having a centrally located rectangular slot, secured inside the metal shell; an upper center contact extending through the slot in said washer and secured together with a thermostatic element to the boss 20 in the lower compartment; a lower center contact secured in the slot in the bottom of the body member; a threaded shell secured on the lower end of the body member; said shell having upwardly extending tongues bent into the piercings 25 in the lugs of the metal shell contained in the upper compartment; and a ring contained in the circumferential groove for clamping the body parts together.

LOUIS LUDWIG. 30
